Primary Examiner — Ramzi S Almatrahi(74) *Attorney, Agent, or Firm* — Knobbe, Martens, Olson & Bear, LLP(57) **CLAIM**

The ornamental design for a camera, as shown and described.

DESCRIPTION

FIG. 1 is a rear perspective view of a camera;

FIG. 2 is rear view thereof;

FIG. 3 is a front view thereof;

FIG. 4 is a side view thereof;

FIG. 5 is a top and front perspective view thereof, shown in condition of use with a pair of eyeglasses disclosed in broken lines to illustrate an environment;

FIG. 6 is a front view thereof;

FIG. 7 is a rear view thereof;

FIG. 8 is a side view thereof;

FIG. 9 is a bottom view thereof; and,

FIG. 10 is a top view thereof.

The broken lines depict portions of the camera in which the design is embodied that form no part of the claimed design. Additionally, the broken lines showing a pair of eyeglasses in FIGS. 5–10 represent environmental structure and form no part of the claimed design.
